SOLUTION FOR DESENSITIZING METAL PLATES USED IN THE LITHOGRAPHIC ART

William N. Misuraca, Merrick, N. Y.

No Drawing. Application March 5, 1938,
Serial No. 194,075

2 Claims. (Cl. 101—149)

My invention consists of the combination of chrome-alum and gum arabic, to produce a desensitizing solution for the non-design areas of metal plates used in the lithographic art; it being the function of said desensitizing solution to confine the printing or ink-taking surface of the plates to the design portions thereof, thus insuring a print within the boundaries of the design portions.

What I claim is:

1. A process of desensitizing the non-printing

portions of the surface of a metal lithographic plate, which consists of treating the image bearing surface of the plate with an aqueous solution of gum arabic and chrome alum.

5 2. A process of desensitizing the non-printing portions of a metal lithographic plate, which consists of creating a hydroscopic film on the plate by the application of an aqueous solution of gum arabic and chrome alum.
